AUTOMATIC FEEDER FOR ANIMALS

Ronald S. Blough, 700 S. D St., Fairfield, Iowa

Filed Nov. 24, 1958, Ser. No. 53,508

Term of patent 14 years

(Cl. D12—2)

FIG.1

FIG.2

FIG.4

FIG.3

Fig. 1 is a perspective view of an automatic feeder for animals, showing my new design.

Fig. 2 is a side elevational view thereof.

Fig. 3 is a cross sectional view taken along lines 3—3 of Fig. 2.

Fig. 4 is a view similar to Fig. 2 but shown partially in vertical cross section.

I claim:

The ornamental design for an automatic feeder for animals, substantially as shown.
